UNITED STATES PATENT OFFICE.

HERMAN SCHREIER, OF SHEBOYGAN, WISCONSIN.

ATTACHMENT FOR HOLDING DENTURES.

1,242,989.

Specification of Letters Patent. Patented Oct. 16, 1917.

Application filed July 13, 1917. Serial No. 180,356.

To all whom it may concern:

Be it known that I, HERMAN SCHREIER, a citizen of the United States, and resident of Sheboygan, in the county of Sheboygan 5 and State of Wisconsin, have invented certain new and useful Improvements in Attachments for Holding Dentures; and I do hereby declare that the following is a full, clear, and exact description thereof.

10 My invention relates broadly to dental appliances, more particularly to means for holding upper and lower dentures in place.

The principal object of my invention is to provide means for holding an upper denture in position when the roof of the user's 15 mouth is too flat to retain the plate by the usual vacuum method.

Another important object of my invention consists in the provision of means for allowing the lower denture to move laterally with respect to the upper to correspond to the lateral movement of the lower jaw.

An additional object is to provide a simply constructed attachment of the foregoing 25 class, which can be inexpensively manufactured and applied, and when in place in the user's mouth, will be in such position that its presence will not be noticed.

With these and other objects in view the 30 invention resides in the novel features of construction, combination and arrangement of parts, which will be hereinafter more particularly described, claimed, and shown in the drawings wherein:

35 Figure 1 represents a side elevational view of upper and lower dentures having my invention attached thereto.

Fig. 2 is a vertical sectional view taken substantially on the plane of the line 2—2 40 of Fig. 3, certain portions of the device, which would not appear in such a view, being indicated by dot and dash lines.

Fig. 3 is a horizontal section on the plane of the line 3—3 of Fig. 2, various positions 45 of the movable portion of the lower jaw part of the device being indicated by dot and dash lines.

In the accompanying drawing wherein 50 similar reference characters are applied to like parts, it will be noted that my invention is applicable to dentures of ordinary shape and construction, such dentures being shown in Fig. 1 designated by the numerals 1 and 2, the upper bearing the numeral 1,

55 while the numeral 2 is applied to the lower.

The teeth of the dentures are held in the plate portions thereof in any preferred manner and the latter are constructed of vulcanized rubber or similar materials such as are ordinarily used.

60 The dentures 1 and 2 are held together by my improved attachment which consists of two members A, each of which are substantially alike, one being disposed on each side of the mouth of the user of the dentures. 65 Since both of the members A are alike, it will be necessary to describe only one in detail. This consists of two jaws 3 and 4 which are vertically alined and are attached respectively to the upper and lower dentures 1 and 2, as shown in Fig. 1. The length of the jaws is immaterial, they being 70 of such size as to readily accomplish their desired functions. The ends of the jaws remote from their attaching portions are 75 provided with circular enlargements 5 and 5'. A pivot pin 6 extends through the central portions of the enlargements 5 and 5' to hold the same together and to permit the outer ends of the jaws 3 and 4 to move toward and away from each other upon similar movement of the dentures.

80 From Fig. 3 it will be noted that the enlargements 5 and 5' are each about one half the width of the jaws so that when said enlargements are pivoted together they will occupy a space of the same width as the jaws. Also, from Fig. 2 it will be noted 85 that the adjacent face of each enlargement is provided with an annular recess 7 for the reception of a coiled spring 8 which surrounds the pivot pin 6, one end of said spring being secured to the enlargement 5, while the other end is connected to the enlargement 5'. This spring is so constructed that its tension 90 will cause the jaws 3 and 4 to normally move apart, whereby when the user opens his mouth the dentures will be moved apart a similar distance, the upper denture being retained in tight engagement with the roof 95 of his mouth. It is obvious that such an arrangement will obviate the necessity of providing a vacuum recess in the top of the denture plate and allow the same to be held 100 in operative position regardless of the shape 105 of the roof of the user's mouth.

To procure the necessary lateral movement of the lower denture with respect to the upper, the lower jaw 4 of each member A is formed of two parts 4^a and 4^b, the free 110

2
end of the latter part being bifurcated to receive an ear 9 on the inner end of the first mentioned part 4^a. These parts 4^a and 4^b are hinged together by means of a pivot pin 10 extending therethrough. The outer ends of the furcations and the ear 9 are rounded as shown in Fig. 3, they preferably being concentric with the center of the pivot pin 10 to procure a wide range of movement between the two parts.

The foregoing means for obtaining horizontal movement of the outer ends of the arms 4 is merely one arrangement, it being obvious that any other similar means could be very well employed. When this arrangement is used the portions 4^a of the jaws 4 are preferably loosely attached to the lower denture 2, but when the two parts of the lower jaws 4 are linked together, or otherwise loosely connected, the outer ends 4^a may be fixed to the lower denture.

From the above description taken in connection with the accompanying drawing, it will be seen that an extremely simply constructed and efficient attachment has been provided whereby ordinary dentures may be conveniently held in position without discomfort to the user. The means for providing lateral movement of the lower denture with respect to the other is also of simple construction and will be very efficient in operation.

I claim:

1. A device for holding dentures in position comprising a pair of jaws, each having an enlargement at one end, the adjacent face of each enlargement having a cavity, a pivot pin extending through the enlargements to hold the jaws together, and a spring in said cavities to normally force the jaws apart. 40

2. A device to be worn in a person's mouth and adapted for holding dentures in position comprising a pair of jaws pivoted together, and means for normally forcing said jaws apart, said jaws being movable 45 vertically away from each other, one of said jaws being hinged to permit one portion to move laterally in a horizontal plane.

3. A device to be worn in a person's mouth and adapted for holding dentures in position comprising a pair of jaws pivoted together, means for moving the outer ends of said jaws vertically away from each other, the lower jaw being formed of two parts, and means for pivotally connecting the two parts of the lower jaw to permit the outer end of the same to move laterally in a horizontal plane. 55

In testimony that I claim the foregoing I have hereunto set my hand at Milwaukee, in the county of Milwaukee and State of Wisconsin. 60

HERMAN SCHREIER.
